UNITED STATES PATENT OFFICE.

FRANK H. ARMSTRONG, OF VULCAN, MICHIGAN.

TRIPPING DEVICE FOR SHOVEL-DIPPER DOORS.

1,154,157.

Specification of Letters Patent. Patented Sept. 21, 1915.

Application filed July 21, 1914. Serial No. 852,132.

To all whom it may concern:

Be it known that I, FRANK H. ARMSTRONG, a citizen of the United States, residing at Vulcan, in the county of Dickinson and State of Michigan, have invented new and useful Improvements in Tripping Devices for Shovel-Dipper Doors, of which the following is a specification.

The invention relates to a tripping device for a shovel dipper door. The primary objects of the invention are to provide a very simple and positive device which will withdraw the catch without fail, and which is automatically set by the normal movements of the dipper. One embodiment of the invention is shown in the accompanying drawings wherein—

Figure 1 is a side elevation of the tripping device when the dipper handle supporting the dipper is in substantially horizontal position and the dipper is ready to discharge, the full lines showing the parts before the tripping device has been actuated and the dotted lines showing the said parts after actuation and after the door has swung to open position, Fig. 2 is a bottom plan view of the dipper and tripping mechanism of Fig. 1, Fig. 3 is a side elevation showing the parts when the dipper handle is in vertical position and the door of the dipper is becoming latched and the tripping mechanism becoming set, and Fig. 4 is a sectional view of a modification.

Referring to the general arrangement of parts as shown in Fig. 1; 1 is the dipper handle which may be of any type and operated in any desired manner; 2 is the dipper carried by the dipper handle; 3 is the door of the dipper provided with the hinge members 4 pivoted at 5, and 6 is the latch by means of which the door is held closed.

The latch 6 slides through straps or loops 7 and 8 carried by the bottom of the door 3 as indicated in Fig. 2, and its right hand end engages a recess 6' carried by the body of the dipper so that when the latch is in the position indicated in Figs. 1 and 2 the door is held against opening movement. My invention consists in the provision of an improved means for insuring the positive withdrawal of the latch from its locking recess when it is desired to dump the contents of the dipper.

Mounted upon the lower side of the end 55 of the dipper handle 1 is a bracket 9, which bracket carries a transverse shaft 10 to

which are non-rotatably secured the arms 11 and 12, the latter of which carries the operating weight 13. A spring held catch 14 engages the end of the lever 11 and serves to hold the weighted arm 12 against downward movement. A third arm 15 carried by the shaft 10 serves to operate the flexible connection 16, such connection secured to the latch 6 by means of the links 17 and 18 (Fig. 2). A solenoid 19 or some other suitable means serves as a means for tripping the catch 14, the solenoid being provided with a core 20 which is drawn through the coil to trip the catch when a current is sent through the coil. A spring 21 serves to retract the coil when the circuit is broken.

Starting with the parts in the positions as illustrated in Figs. 1 and 2 the operation is as follows: The dipper 2 being full of material to be dumped, and being positioned over the spot at which it is desired to discharge, current is sent through the coil 19 thus causing the core 20 to be drawn down and tripping the catch 14. The release of the catch 14 permits the weighted arm 12 to swing downward thus rotating the shaft 10 and moving the lever 15 to the left. This causes the withdrawal of the latch 6 through the actuation of the connections 16, 17, and 18. In order to make this action more positive, the flexible connection is preferably provided with a slight amount of slack so that a jerk is secured as the weight falls. The weight 13 may be made as heavy as is necessary to secure the desired certainty of action, and it will be seen that the amount of power required to trip the apparatus is very slight, since the catch 14 is easily released. A powerful and certain action is thus secured with the expenditure of only a slight amount of conveniently applied power. Upon the release of the parts as above described the weighted lever 12 and the door 3 move to the position indicated in Fig. 1 in dotted lines thus permitting the material in the dipper to discharge by gravity.

The manner in which my tripping device automatically resets itself will be readily understood by reference to Fig. 2 which illustrates the parts in the position assumed when the dipper handle and the dipper carried thereby are swung to upright position, this being the position to which the parts are moved in order to close the door and in order to bring the dipper to digging position. It will be seen that when the parts

move to this position of Fig. 3 the weighted arm 12 naturally swings to the vertical position illustrated and that the door 3 is swung shut. When the door 3 swings shut the 5 heavy latch 6 falls by gravity into locking position. Similarly when the arm 12 swings a trifle farther to the right the end of the arm or lever 11 is engaged by the catch 14 and the parts are in the position for a repetition 10 of the operation theretofore described when the dipper handle and dipper move to their lateral position as indicated in Fig. 1. The engagement of the latch 14 with the end of the arm 11 is insured, since in the 15 normal operation of the device, the dipper is swung to the left of the vertical position indicated in Fig. 3, thus making certain that the catch will properly engage.

In the modification of Fig. 4, the ball 22 20 takes the place of the weight 13 of the other construction. This ball is mounted in the cylinder 23, and when the dipper handle 24 is in its horizontal position, the ball is held in the position illustrated by the catch 25. 25 When the catch is released by the solenoid 26, the ball drops striking the member 27 and actuating the bell crank 28 to pull the connection 29 and withdraw the dipper door latch. The operation of setting the device 30 when the handle 24 is swung to a vertical position is similar to that already described in connection with the other construction.

What I claim is:

1. The combination with a dipper having 35 a door and a latch therefor and mounted for movement so as to occupy either an upright position or a lateral position, of means for withdrawing the latch when the dipper occupies its lateral position comprising a weight, a catch for maintaining the weight in a relatively elevated position, connections for withdrawing the said latch arranged so as to be operated by the said weight when it is released, and means for releasing the said 45 catch to permit the weight to fall and operate the connections to withdraw said latch, the parts being arranged so that the movement of the dipper to substantially upright position serves to return the weight to its 50 original position with respect to the catch and dipper.

2. The combination with a dipper having

a door and a latch therefor and mounted for movement so as to occupy either an upright or a lateral position, of means for withdrawing the latch when the dipper occupies its lateral position comprising a pivoted laterally extending arm provided with a weight, a catch for maintaining the arm with its weight in its laterally extending position, 60 connections between the arm and the said latch, and means for releasing the said catch to permit the arm to swing downwardly under the influence of the weight and release the said latch, the movement of the dipper 65 to upright position serving to return the said arm with its weight to its original position with respect to the catch and dipper.

3. In combination, a dipper mounted for movement so as to occupy either an upright 70 or a lateral position, a door hinged to the dipper and constituting the bottom thereof, a latch which locks automatically when the door is closed, a pivoted arm provided with an operating weight and extending laterally 75 when the dipper occupies its lateral position, a connection from the arm to the said latch, a catch for maintaining the arm in its lateral position, and means for withdrawing the catch to permit the weight to swing the 80 said arm and withdraw the said latch, the said catch being adapted to automatically reengage when the dipper moves to its vertical position and the door is latched.

4. The combination with a dipper having 85 a door and a latch therefor, and mounted for movement so as to occupy either an upright or a lateral position, of a weighted arm which occupies an upright position when the dipper is in its upright position, an automatic catch which holds the arm against movement with respect to the dipper as the dipper and arm are moved to their lateral positions, means for releasing the catch, and connections between the said latch and the 90 arm whereby the latch is withdrawn as the weighted arm swings to its upright position. 95

In testimony whereof I have hereunto signed my name in the presence of the two subscribed witnesses.

FRANK H. ARMSTRONG.
